UNITED STATES PATENT OFFICE.

ARTHUR M. BELL, OF BELLEVILLE, ILLINOIS, ASSIGNOR, BY MESNE ASSIGNMENTS, TO NATIONAL CARBON COMPANY, INC., OF CLEVELAND, OHIO, A CORPORATION OF NEW YORK.

MACHINE FOR POINTING CARBONS.

1,255,693.

Specification of Letters Patent.

Patented Feb. 5, 1918.

Application filed October 18, 1917. Serial No. 197,299.

To all whom it may concern:

Be it known that I, ARTHUR M. BELL, a citizen of the United States, residing at Belleville, in the county of St. Clair, State of Illinois, have invented certain new and useful Improvements in Machines for Pointing Carbons; and I do hereby declare the following to be a full, clear, and exact description of the invention, such as will enable others skilled in the art to which it app pertains to make and use the same.

The present invention relates to machines for pointing rods and particularly carbon rods, such as are used as electrodes for dry batteries. In the manufacture of dry batteries, these rods are in some cases forced into the material forming the depolarizing mixture, and for convenience in performing this operation, it is of assistance if the rods be pointed at one end.

In accordance with the present invention mechanism is provided by which the pointing operation is in a large measure automatic. More particularly, means is provided by which rods may be fed automatically one at a time into chucks mounted on a movable head by which they are conveyed to a properly beveled grinding wheel whereby the rods are pointed. Further movement of the head then brings the finished rods into a position where each one is forced out of its holding chuck by a new rod that is being supplied to the chuck.

The machine is of simple construction, has few moving parts, the operation of pointing the rods may be quickly performed and the entire machine is automatic in its action. The particular nature of the invention and other objects and advantages thereof will appear most clearly from a detailed description of a preferred embodiment thereof as illustrated in the accompanying drawings in which Figure 1 is an elevation of one side of the machine; Fig. 2 is a front elevation; Fig. 3 is a view principally in section along the line 3—3 of Fig. 2; Fig. 4 is an elevation of the other side of the machine; Fig. 5 is a detailed view of one of the chucks for holding the rods and Fig. 6 is a sectional view on the line 6—6 of Fig. 3.

Throughout the several views similar reference characters denote similar parts. The

moving parts of the machine are mounted upon a pedestal or support 10 provided with a flat base 11, which may be attached to the floor. The pedestal which may be of any desired construction is here shown as comprising two sections bolted together as at 12. A bracket 13 is attached to the front face of the pedestal and this bracket is provided with split clamping members 14 within which a sleeve 15 may be retained in any desired position of adjustment by means of bolts 16. The sleeve is provided with adjustable collars 17 to prevent longitudinal movement. Attached to one end of the sleeve is an arm 18 which is provided with a lug 19 through which is threaded an adjusting screw 20, the inner end of which is rotatably connected to the upper section of the pedestal as at 21. Attached to the free end of arm 18 is a pin 22 which is formed at its outer end with an enlarged head 23 to serve as a support for certain parts of the apparatus as will hereinafter appear.

Rotatably mounted on the shank of the pin 22 is a rotary head 24 which as shown most clearly in Fig. 3, is composed of a sleeve portion 25 surrounding the pin 22 and a circular disk portion 26 formed for a part of its diameter of about twice the thickness of the outer portion. An annular plate 27 is attached to the thicker part of the portion 26 by means of bolts 28. There is thus formed between the outer part of portion 26 and the plate 27, a channel to accommodate the chucks used for holding the carbon rods.

Each of the chucks, as shown most clearly in Figs. 2, 3 and 5, comprises a gear wheel 30 mounted upon a hub 31 which is mounted in bearings in the members 26 and 27 of head 24. The hub is provided with an aperture through its center of a size corresponding to the rods which are to be held in the chuck and preferably the outer end of the hub is provided with a depression as at 32 to aid in guiding the rods into the aperture. Attached to the inner end of the hub is a box 33 containing a number of sliding plungers 34, the outer ends of which are engaged by springs 35 attached to the outer surface of the box by screws 36. The plungers 34 are of such length that when a rod is inserted between their inner ends,

- they will be forced outwardly against the action of the springs 35 which will thus retain the rod firmly in place within the chuck.
- 5 The head 24 which carries the chucks may be rotated by means of a gear wheel 38 fixed upon the sleeve 25 of the head and adapted to be driven by a sprocket chain 39 passing over a sprocket pinion 40 attached to a shaft 10 41 which is rotatably mounted in the sleeve 15 and carries at the other end a pulley 42 driven by a belt 43 running over a pulley 44 mounted on a stub shaft projecting from the pedestal of the machine near its base.
- 15 A large pulley 45 is associated with pulley 44 and by means of a belt 46 is connected to a pulley 47 at the end of a shaft 48 which is mounted in bearings 49 at the top of the pedestal. Shaft 48 is provided with a driving pulley 50 through which power may be supplied to the machine. Near the other end of shaft 48 is a grinding wheel 51, the edge of which is formed of proper bevel to produce the desired amount of pointing of 20 the rods. Fixed upon the shaft 48 beyond the grinding wheel is a pulley 52 which by means of a belt 53 is connected to a pulley 54 loosely mounted upon the end of the shaft 41 and retained in place by a collar 55 25 attached to this shaft. A sprocket pinion 56 is fastened to pulley 54 and over this pinion passes a sprocket or silent chain 57 which as shown most clearly in Figs. 1 and 4, engages at diametrically opposite points 30 of the head 24, the gear wheels 30 associated with the chucks for holding the rods. Above the head 24, the chain 57 passes over an idler sprocket pinion 58 mounted on a bracket 59 which is attached to the top of 35 the enlarged head 23 of the pin 22. A brake 60 is mounted upon the arm 18, and is provided with a friction lining which engages the hub portion of the gear wheel 38.
- 40 The mechanism for automatically feeding the rods into the chucks and removing them therefrom is mounted upon the enlarged head 23 of the pin 22. The rods are supplied from a hopper 61 mounted at one side of the machine and provided with a discharge passage 62 which will permit only 45 one rod at a time to be fed from the hopper. As the rods pass out of the hopper, they roll along a shelf 63 and finally drop into a semi-circular groove or trough 64 which registers 50 with the aperture through the hub of each chuck as the chuck passes opposite the end of the trough. For forcing the rods out of this trough and into the chucks, a finger or pusher 65 is slidably mounted upon the shelf 55 63 and is connected by means of a link 66 to one end of a lever 67 which is placed within a slot in the head 23 and pivoted at 68. A spring 69 connected at one end to the lever and at the other end to a bracket 70 65 mounted upon the head 23, serves to retain the finger normally at the outer end of the trough 64. For actuating lever 67, there is provided a plunger 71 mounted in a slot at the side of the head 23 and having a roller 72 mounted on the end of a stud 73 which extends through a slot in a guiding plate 74 attached to the side of the head 23. The roller is adapted to be engaged by cam dogs 75 mounted upon the outer face of the rotatable chuck head 24, there being as many 75 of these dogs as there are chucks.
- 78 For the purpose of insuring that the rods shall be held firmly against the beveled edge of the grinding wheel, a roller 76 is adjustably mounted upon the end of a rod 77 80 which is pivoted to the support at the point 78. The roller 76 is so mounted with respect to the rotatable head 24 that it engages the outer end of each rod as it is brought into grinding position. A chute 79 is provided for conveying away the finished rods after they are removed from the chucks by the new rods that are being supplied to the machine.
- 85 In the operation of the machine described 90 above, the shaft 48 is continuously driven at the desired speed by power pulley 50. The pulley 52 will be driven at the same speed and will through the belt 53 and pulley 54 drive the sprocket or silent chain 57 which 95 will rotate the two chucks which at this time occupy positions opposite the feeding slot 64 and adjacent the grinding wheel 51. All of the other chucks will not be driven until in turn they come into these positions. From the pulley 47 on the shaft 48, the 100 shaft 41 will be driven at considerably reduced speed through the belts 46 and 43 and pulleys 45, 44 and 42 with the result that head 24 which carries the chucks will be continuously rotated from shaft 41, but at a speed so slow that each chuck will be in position adjacent the rapidly rotating grinding wheel for a sufficient length of time to 105 effect the proper tapering of the rods. The 110 rapidity of the grinding action will also be increased due to the fact that each chuck as it comes into position adjacent the grinding wheel will be given a rapid rotation by means of the chain 57. At the same time 115 that the grinding operation is being performed, one of the dogs 75 will have come into position to engage the roller 72 and force it outwardly, thus moving the plunger 71 to swing one end of the lever 67 outwardly while the inward motion of the other end of this lever will, by means of finger 65, push a rod out of the trough 64 into the chuck which at this time lies adjacent the end of the trough. If at this time, the 120 chuck contains a rod which has been pointed, the new rod will force the pointed rod out into the discharge chute 79. The motion of the rotating head carrying the chucks will be slow enough to permit the operation of 125 130

feeding in a new rod and removing a pointed rod while each chuck is passing by the end of the trough 64. As soon as the cam 75 disengages the roller 72 springs 69 will 5 restore the finger 65 to its normal position and the rotating head will gradually carry the rod toward the grinding wheel. By means of the screw 20, the arm 18 may be given a fine adjustment to bring the parts 10 mounted upon the arm into such a position that the rods may be brought into proper relation to the beveled edge of the grinding wheel.

The provision of the brake 60 helps to 15 produce a smoothly running machine and prevents a jerky motion of the rotatable head at the time when the rods pass out of contact with the grinding wheel.

While an embodiment of the invention 20 especially adapted for pointing carbon rods such as are used for the electrodes of dry batteries has been shown, it will be understood that the machine is adapted to a wide variety of uses in pointing rods of any material. It will also be understood that various changes in the details of the construction of the machine may be made without departing from the principle of the invention.

30 I claim:

1. In apparatus for pointing rods, the combination of a support, grinding means mounted upon the support, a plurality of rod holding means, means mounted on the 35 support for carrying the rod holding means, means for moving said carrying means to bring the rods into coaction with the grinding means, and means for feeding rods into the rod holding means.

40 2. In apparatus for pointing rods, the combination of a support, grinding means mounted on the support, a plurality of rod holding means, means upon which said rod holding means are mounted, means for moving 45 said last named means to bring the rods into coaction with the grinding means, and means for rotating each rod holding means when the same comes into position adjacent the grinding means.

50 3. In apparatus for pointing rods, the combination of a support, grinding means rotatably mounted upon the support, a plurality of tubular members through which rods may be fed, clamping means associated 55 with said hollow members for holding rods in place therein, means upon which the hollow members are mounted and means for moving said last named means to bring the rods successively into coaction with the grinding means.

60 4. In apparatus for pointing rods, the combination of a pedestal, grinding means rotatably mounted on the pedestal, a plurality of rod holding means, rotatable supporting means for the rod holding means,

means for rotating the supporting means to bring the rods into coaction with the grinding means and means mounted adjacent the supporting means for feeding the rods into the holding means.

5. In apparatus for pointing rods, the combination of a pedestal, grinding means rotatably mounted on the pedestal, a plurality of rod holding means, rotatable supporting means for the rod holding means, 75 means for rotating the supporting means to bring the rods into coaction with the grinding means, means mounted adjacent the supporting means for feeding the rods into the holding means and means actuated by the 80 supporting means for actuating said feeding means.

6. In apparatus for pointing rods, the combination of grinding means, a plurality of rod holding means, rotatable supporting 85 means for the rod holding means, means for rotating the supporting means to bring the rods into coaction with the grinding means, means for rotating each rod holding means when it comes into position adjacent the 90 grinding means and means for pressing the ends of the rods against the grinding means when they are in position to be ground.

7. In apparatus for pointing rods, the combination of rotatable grinding means, 95 a plurality of chucks for holding the rods, a circular rotatable member upon which said chucks are mounted, means for rotating said member to bring the chucks successively into position adjacent the grinding 100 means and means for rotating each chuck when it is in position adjacent the grinding means.

8. In apparatus for pointing rods, the combination of grinding means, a plurality 105 of rod holding means, rotatable means upon which said rod holding means are supported, means for rotating said supporting means to bring the rods successively into coaction with the grinding means and means 110 for rotating each rod holding means when it comes into position adjacent the grinding means and for rotating each rod holding means when it is in position to have a new rod supplied thereto.

9. In apparatus for pointing rods, the combination of grinding means, a plurality of rod holding means, means upon which said rod holding means are supported, means for moving said supporting means to bring the rods successively into coaction with the grinding means, a hopper mounted adjacent the supporting means, a trough in the hopper adapted to receive the rods, means above the trough for feeding rods from the 120 trough to the rod holding means and means for controlling the operation of the rod feeding means.

10. In apparatus for pointing rods, the combination of grinding means, a plurality 125

- of rod holding means, means upon which said rod holding means are supported, means for moving said supporting means to bring the rods into coaction with the grinding means, means for supplying new rods and ejecting finished rods from the rod holding means and means actuated by movement of the supporting means for actuating said supplying and ejecting means.
- 10 11. In apparatus for pointing rods, the combination of grinding means, a rotatable member mounted adjacent the grinding means, a plurality of chucks mounted near the periphery of said member, each of said chucks comprising a hub rotatably mounted in said member, a plurality of spring pressed rod holding plungers at one end of the hub and a gear wheel fixed upon the hub, and means passing over the outer edge of said member 15 adapted to engage and rotate the gear wheels of the chucks.
12. In apparatus for pointing rods, the combination of a rotatable grinding wheel, a rotatable member mounted adjacent the 20 grinding wheel, a plurality of rod holding means mounted upon the rotatable member, means for causing rotation of each rod holding means when it comes into position adjacent the grinding means and means for 25 driving said rotating means from said grinding means.
13. In apparatus for pointing rods, the combination of a support, grinding means mounted upon the support, a plurality of 30 rod holding means, supporting means upon which said rod holding means are mounted, means for moving said supporting means to bring the rods into coaction with the grinding means and means for adjusting 35 the relative position of said grinding means and supporting means to permit the rods to 40

be brought into contact with said grinding means.

14. In apparatus for pointing rods, the combination of a support, grinding means 45 rotatably mounted at the top of the support, a member pivotally mounted on a side of the support, a rotary member on said pivoted member, a plurality of rod holding means on the rotary member and means for 50 adjusting the position of said pivoted member to cause the rod holding means to be brought into proper relation to the grinding means.

15. In apparatus for pointing rods, the 55 combination of a support, grinding means rotatably mounted on the support, an arm pivoted on the support, means for adjusting the position of the arm, a pin on the free end of the arm, a rotary member mounted on the pin, a plurality of rod holding members on the rotary member, means mounted on the outer end of the pin for feeding rods into the rod holding members, and means on the rotary member for ac- 60 tuating the rod feeding means.

16. In apparatus for pointing rods, the combination of a support, grinding means rotatably mounted on the support, a sleeve 70 adjustably mounted on the support, an arm on the sleeve, a pin mounted on the end of the arm, a rotary member on the pin, a shaft mounted in the sleeve, means for driving the rotary member from the shaft, a plurality of rod holding means mounted 75 on the rotary member, means rotatably mounted on the shaft for rotating the rod holding means and means driven from said grinding means for driving said rod holding rotating means.

In testimony whereof I affix my signature.

ARTHUR M. BELL.
